UNITED STATES PATENT OFFICE.

WILLIAM L. HANSEN AND ALFRED HAYES, OF COALVILLE, UTAH.

AUTOMATIC DEVICE FOR DUMPING CARS.

No. 817,972.

Specification of Letters Patent.

Patented April 17, 1908.

Application filed August 24, 1904. Serial No. 222,020.

To all whom it may concern:

Be it known that we, WILLIAM L. HANSEN and ALFRED HAYES, citizens of the United States, residing at Coalville, in the county of Summit and State of Utah, have invented a new and useful Improvement in Automatic Devices for Dumping Cars, of which the following is a specification.

This invention relates to improvements in side-dump tipples; and the object is to provide an automatic device which will tip the car to one side, the car being held in the meantime upon the trestle, and counterweights being employed to return the car, when emptied, to an upright position.

Our invention also consists of the novel features of construction and combination of parts hereinafter described, particularly set forth in the claims, and shown in the accompanying drawings, in which—

Figure 1 is a plan view of the device. Fig. 2 is a side elevation showing a car held upon the tipple. Fig. 3 is a vertical section on the line 3-3 of Fig. 2. Fig. 4 is a detail side elevation of the brake device, and Fig. 5 is a detail perspective view of a tripping mechanism.

In the drawings, A represents a suitable platform or trestle upon which the car B, illustrated as a mine-car, is switched. The material to be dumped is deposited upon the side of the platform A. Running lengthwise of the platform A is the tipple-shaft C, journaled in bearing carried by the ends of the platform. A brake-wheel C¹ is arranged upon one end of the tipple-shaft C, and over the wheel passes a brake-band C². One end of this band is held fixed and the opposite end is secured to a pivoted brake-lever C³, working on a rack-segment C⁴. Secured on the shaft and at right angles to the same are a plurality of cross-ties D, the portion of the shaft carrying the same being preferably squared. Arranged upon these ties are the rails D', forming a track alining with the tracks D². On the shaft and depending below the same are the sector-shaped counterweights E, which normally hold the shaft in such a position that the track formed by the rails D' is held in a horizontal position. The weight E has a finger E¹, which, as the tipple dumps, engages a rope E², which is suspended below the track and runs over a pulley E³ and is secured to a weight E⁴, which is raised by reason of the engagement of the rope by the finger E¹ of the weight. This checks too rapid movement of the tipple in dumping and aids, by descent of

the weight, in restoring the parts to their normal position.

The ties D on one side of the truck project a sufficient distance to rest on the longitudinal side beams of the platform A, as shown in Figs. 1 and 3, and the track is held from tipping upon that side, which may be either the right or left side, but is free to tip in the opposite direction. In the central portion of this track-section, supported by the shaft C, is arranged means for holding the car on the track when the tipple-shaft is rotated to tip the car. These means consist of vertical standards arranged on the ties D, as shown at F, said standards being carried by the end portions of the ties D, the intermediate portions of the standards F being bowed or angled outwardly, and at their upper ends they carry parallel bars F², one on each side of the track, which are adapted to engage the peripheries of the wheel B' of the car at a point diametrically opposite the portion of the wheel-tread bearing on the rails D'. On one of the ties D between the rails D' we arrange bell-crank levers G, pivoted to the tie at the juncture of the arms of the bell-crank, and one arm of each bell-crank G is adapted to be projected over the adjacent rail D' in advance of the front wheels B' of the car B when the said car has reached its position, as shown in Fig. 2, with the wheels in engagement with the bars F². It will be noted that the outer rail D'—that is, the rail farthest from the beam of the platform A, upon which the ties rest—is farther from the shaft C than the rail D', adjacent the side of the platform A; but the track is held in its horizontal position by the weights E. When, however, a loaded car is run upon the said track-section formed by the rails D', the load of the car is off center with respect to the shaft and the car will be automatically dumped; but when the load is off the weight E will restore the track and car to their normal positions. To prevent too rapid dumping, which might tend to dislodge the car from the track, and to prevent the car dumping before the proper position has been reached, is the object of the brake wheel and band, the action of the band being controlled by the lever C³, and the tipping of the track-section can thus be controlled.

The track-section formed by the rails D' has a grade sufficient to permit the car to run off as soon as the bell-cranks G are withdrawn from in advance of the wheels of the car. To accomplish this automatically, we

connect the rods G' pivotally to the inner ends of the bell-crank and to a sliding plate G^2 . An upright lever G^3 , pivoted intermediate its ends to any suitable bracket, is pivotally connected at its lower end to the plate G^2 . A second car in advancing in the tipple will strike and throw the tripping-lever G^3 , withdrawing the bell-cranks G from in advance of the wheels of the preceding car, and it will be struck and forced from the tipple, provided the track-section is substantially horizontal and the grade is omitted, as may be the case. A spring G^4 is employed to throw the parts to their normal position after the car passes the tripping-lever G^3 .

After the car has passed the tripping-lever G^3 and the spring G^4 has again set the bell-cranks the car strikes a weighted rod H , pivoted between its end and held by its lower weighted end in a normally vertical position. When the car has passed this rod or bar H , its front wheels are caught and locked by the bell-cranks G , and the bar H rises on the rear side of the car-axle and prevents a recoil movement of the car, as the stop H' prevents rearward movement of the bar H .

Having thus fully described our invention,

what we claim as new, and desire to secure by Letters Patent, is—

1. The combination with a platform, a shaft carried horizontally thereby, a brake-wheel carried by the shaft, a brake-band, a lever adapted to regulate the pressure of the band upon the brake-wheel, a track-section carried by the shaft, the outer rail of the track being a greater distance from the shaft than the inner rail, and counterweights depending from the shaft and adapted to hold the track-section in normally a horizontal plane.

2. The combination with a tilting track-section, of bell-crank levers pivotally carried by said section and normally projecting across the track-rails, a slideable plate carried by the section, a tripping-lever pivotally connected to the plate, a spring adapted to return the plate to its normal position, and rods pivotally connected at one end to the inner ends, respectively, of the bell-crank levers, and at their opposite ends to the plate.

WM. L. HANSEN.
ALFRED HAYES.
